UNITED STATES PATENT OFFICE.

HERMAN L. MELTZER, OF NEW YORK, N.Y.

REVERSIBLE GARMENT.

SPECIFICATION forming part of Letters Patent No. 365,841, dated July 5, 1887.

Application filed November 23, 1886. Serial No. 219,607. (No model.)

To all whom it may concern:

Be it known that I, HERMAN L. MELTZER, a resident of New York city, in the county and State of New York, have invented a new and useful Improvement in Garments, of which the following is a specification.

This invention consists in a garment which is provided with buttons and button-holes, the former being secured to the garment at a point contiguous to the boundary of the latter, whereby the button is adapted to be passed through the button-hole without being detached from its fastening and to occupy a position upon either side of the garment, all substantially as hereinafter described and shown.

The invention also consists in a reversible garment which is provided with body, skirt, and cape portions, which latter is made integral with the material comprising the skirt portion, the sack or body portion thereof made separate from and seamed to the skirt portion, said garment being provided with buttons and button-holes, the former being secured to the garment at a point contiguous to the boundary of the latter, whereby the buttons are adapted to be passed through the button-holes without being detached from their fastenings, and to occupy a position on either side of the garment, all substantially as hereinafter described and shown.

In the accompanying sheets of drawings the garment of the present invention is illustrated, and Figures 1 and 2 are front and rear views of the garment with its side outermost to present the appearance of a "Newmarket" cloak. Figs. 3 and 4 are front and rear views of the garment with its side outermost presenting the appearance of a "Havelock" or cape cloak. Fig. 5 is a view illustrating the garment of Figs. 1 and 2 spread out and showing the inner side thereof. Fig. 6 is a section on line 6 6 of Figs. 2 and 5. Fig. 7 is an enlarged view of a portion of the lapel, illustrating the button and button-hole arrangement whereby the same buttons serve in the use of the garment with either side out. Figs. 8 and 9 are sections on line x x and y y of the same. Figs. 10, 11, and 12 are horizontal or transverse sections of the garment, illustrating the manner of employment of one series of buttons for use when either side of the garment is worn outermost. Fig. 13 is a view

illustrating the formation of the cape portion of the cloak in relation to the skirt portion.

In the drawings, A represents a garment, 55 (here shown in the form of a cloak) of which B represents the body or sack portion, C the skirt, D the sleeves, and E the cape, and the body portion of the garment is adapted to be buttoned at the front. The portion of the garment comprising the waist or body part is made separate from that comprising the skirt portion, and is seamed or sewed thereto. The cape is made integral or in one piece with the skirt portion, and without any seam. 60

This garment is so formed as to be reversed or turned inside out, and when it is, as shown in Figs. 1 and 2, in the form of a Newmarket cloak, the cape lies pendent on the opposite or inner side, as shown in Figs. 5 and 6, and 70 serves to give a form to the garment in the manner of a bustle. When desired, the garment can be reversed, together with the sleeves thereof, the cape portion thrown up over the shoulders, and thus a garment of the form of 75 a cape-cloak is presented. This cape may be provided with buttons, loops, or other fastening devices for securing it in the proper position for wear.

The garment is provided with buttons G 80 and button-holes H, for engaging said buttons and securing the garment closed. The garment is also provided with slits or holes J, at the edge of which holes the buttons G are secured, said buttons being placed upon thread, 85 catgut, wire, or other flexible material, a, in such a manner that they may be made to occupy a position on either side of the material forming the garment, as is particularly shown in the drawings in the views of Sheet 2. 90 When the garment has been worn with either side outermost and it is reversed to be worn with its other side outermost, the buttons are on what would then be the inside or "wrong" side of the garment, and the buttons have simply to be passed through their respective apertures J (their securing-thread a being slack enough to permit) to assume a position on the other or opposite side of the material, and for a proper and practical use. 95

In buttoning the garment, as shown in the drawings, Figs. 1, 7, 10, 11, and 12, each lapel L M respectively has its series of buttons G each with its aperture J, and each lapel has a

series of button-holes H H; and it will be seen from this construction that the garment is what is well known as "double-breasted," can be worn with either side out, and can be 5 buttoned by the buttons of either lapel; and, in addition to the buttons which are on the outside of one lapel and buttoned through the button-holes of the other lapel, the buttons of such other lapel are also presented to view, if 10 desired, or they may be turned in and through their slits J to the inner side of the lapel, and then will not be presented to view.

In the drawings, Fig. 10 is a section representing the garment with one side out—for instance, to form a Newmarket cloak—with its 15 buttons of one lapel, L, buttoned through the button-holes H of the other lapel, M, and the buttons G of such other lapel outermost, as shown; but, if desired, such buttons G may be 20 turned in, as shown in Fig. 11, in which case they would not be exposed to view.

Fig. 12 represents a cross-section of the garment turned with its other side outermost, the buttons G also turned to the then outside, 25 and it will be seen that the buttons G of the other lapel, M, may be turned outermost to view or left within, as shown by the dotted lines.

In Fig. 13 is represented the manner of 30 forming the skirt and cape in one and the same piece of material. It is desirable to so form the cape, as it insures a better set and position in relation to the body portion of the garment, and, when worn outermost, concealing from 35 view the seams by which the skirts are secured to the waist or body.

It is desirable in making these garments to form them of material whose opposite sides differ in appearance—such, for instance, as 40 one having a shaggy or furry texture for one side and a smooth appearance on the other side; and one side may have worked therein

a pattern—such as stripes, checks or other designs—while the other side may be of a uniform color, and thus it will be seen that a garment of the character described may be worn, as described, to present the appearance of two different garments as to the pattern, cut, or shape, and also the appearance of entirely different garments as to the texture of the goods 45 of which it is composed. 50

Having thus described my invention, what I claim, and desire to secure by Letters Patent, is—

1. A garment provided with a button and 55 button-hole, the former being secured to the garment at a point contiguous to the boundary of the latter, whereby the button is adapted to be passed through the button-hole without being detached from its fastening, and to occupy 60 a position upon either side of the garment, as set forth.

2. A reversible garment provided with body, skirt, and cape portions, which latter is made integral with the material comprising the 65 skirt portion, the sack or body portion thereof made separate from and seamed to the skirt portion, and the garment being provided with buttons and button-holes, the former being secured to the garment at a point contiguous to 70 the boundary of the latter, whereby the buttons are adapted to be passed through the button-holes without being detached from their fastenings, and to occupy positions on either side of the garment, as set forth. 75

In testimony that I claim the foregoing as my invention I have signed my name, in presence of two witnesses, this 18th day of September, 1886.

HERMAN L. MELTZER.
